UNITED STATES PATENT OFFICE.

JAMES A. STEVENS, OF NEWBURYPORT, MASSACHUSETTS.

WINDOW-VENTILATOR.

No. 926,617.

Specification of Letters Patent.

Patented June 29, 1909.

Application filed November 5, 1908. Serial No. 461,212.

To all whom it may concern:

Be it known that I, JAMES A. STEVENS, a citizen of the United States, residing at Newburyport, in the county of Essex and State of Massachusetts, have invented certain new and useful Improvements in Window-Ventilators, of which the following is a specification.

This invention relates to window ventilators, and has specially in view certain new and useful improvements therein whereby the same may be readily fitted to any size of window casing without the use of fastening means, and which is so constructed that it will not interfere with the raising or lowering of the window to regulate the amount of air admitted to the room, and at the same time serve as a screen to prevent the entrance of rain, snow, or the like.

In carrying out the objects of the invention generally stated above it will be understood of course that the essential features are susceptible of structural changes and modifications of details, but a preferred and practical embodiment of the same is shown in the accompanying drawings, wherein—

Figure 1 is a perspective view of a window casing showing the improved ventilator therein. Fig. 2 is a perspective view of the frame of the ventilator, the covering thereof being removed. Fig. 3 is a horizontal sectional view taken on the line 3—3, Fig. 1.

Like characters of reference designate corresponding parts.

In the accompanying drawings, 10 designates a window casing of the usual type as seen from the interior of a room, and 11 designates the improved ventilator mounted within the same.

As will be seen by reference to Fig. 2 of the accompanying drawings, the said ventilator 11 is composed of two duplicate frame sections 12—13, each of which is constructed from a single length of wire, bent to form a vertically arranged side member 14 having an inturned, horizontally arranged base extension 15 the end of which is adjustably mounted within a sleeve 16, having set screw or equivalent fastening means 16^a passing thereto to engage with and retain the base extensions of both frame sections in the de-

sired adjusted position in said sleeve. The upper end of said side member 14 of each frame section terminates in an outwardly bowed, horizontally arranged top member 17 having an adjustable engagement with a sleeve 18, provided with set screw or equivalent fastenings 19 for retaining said end portion in the desired, or necessary adjusted position within said sleeve 18.

Upright brace rods 20—21 connect the base extensions 15 with the upper outwardly bowed members 17, said brace rods being also of wire, and preferably arranged adjacent to each end of the sleeves 16 and 18.

A frame covering 22 is suitably secured over each frame section, said covering being of any suitable weatherproof and waterproof material, and may be ornamented.

In fitting the improved ventilator to a window casing, the frame sections are adjusted to the required size, and the frame is contracted slightly to permit of its being sprung into engagement with the side of the casing and the sill, and to be held in such engagement by the expansive force of the said frame. This described engagement between the said frame and the casing obviates the use of disfiguring fasteners, or the employment of holding flanges, as will be obvious.

Another prominent feature of the invention is the bowed formation of the top, which provide a rounded surface that bears against the curtains or tapestries with little or no danger of tearing or otherwise injuring the same.

Claims:

1. A ventilator for windows consisting of two duplicate wire frame sections, each of said frame sections having a vertical side member for engagement with the window frame, a straight lower member, and an outwardly bowed upper member, means for adjustably connecting said upper and lower frame members, and a covering for the entire frame structure.

2. A ventilator for windows comprising two U-shaped frame sections each formed of a single length of resilient material bent to provide a vertical side member having an inturned horizontally arranged lower end

portion and an outwardly bowed upper end portion, coupling sleeves for holding the bowed upper ends and the inturned lower ends, respectively, in adjustable relations, 5 brace rods connecting the upper portion and lower portion of the frame sections, and a covering material for each frame section.

In testimony whereof I hereunto affix my signature in the presence of two witnesses.

JAMES A. STEVENS.
